(57) CLAIM

The ornamental design for an tube with closure, as shown and described.

DESCRIPTION

FIG. 1 is a top perspective view of an tube with closure in a closed condition in accordance with the present teachings. FIG. 2 is a bottom perspective view of the tube with closure of FIG. 1.

FIG. 3 is a side view of the tube with closure of FIG. 1.

FIG. 4 is a top view of the tube with closure of FIG. 1.

FIG. 5 is a bottom view of the tube with closure of FIG. 1.

FIG. 6 is a top perspective view of an tube with closure in a closed condition in accordance with the present teachings.

FIG. 7 is a bottom perspective view of the tube with closure of FIG. 6.

FIG. 8 is a side view of the tube with closure of FIG. 6.

FIG. 9 is a top view of the tube with closure of FIG. 6.

FIG. 10 is a bottom view of the tube with closure of FIG. 6.

FIG. 11 is a top perspective view of an tube with closure in a closed condition in accordance with the present teachings. FIG. 12 is a bottom perspective view of the tube with closure of FIG. 11.

FIG. 13 is a side view of the tube with closure of FIG. 11.

FIG. 14 is a top view of the tube with closure of FIG. 11.

FIG. 15 is a bottom view of the tube with closure of FIG. 11.

FIG. 16 is a top perspective view of an tube with closure in a closed condition in accordance with the present teachings.

FIG. 17 is a bottom perspective view of the tube with closure of FIG. 16.

FIG. 18 is a first side view of the tube with closure of FIG. 16.

FIG. 19 is a top view of the tube with closure of FIG. 16; and,

FIG. 20 is a bottom view of the tube with closure of FIG. 16.
